INVENTOR

WINFIELD E. HINSDALE

BY

Merrill E. Clark
ATTORNEY

UNITED STATES PATENT OFFICE.

WINFIELD E. HINSDALE, OF TRENTON, NEW JERSEY, ASSIGNOR TO THE TRENTON POTTERIES COMPANY, OF TRENTON, NEW JERSEY, A CORPORATION OF NEW JERSEY.

LAVATORY.

Application filed November 2, 1927. Serial No. 230,452.

The present invention relates to lavatories and has for an object to provide an improved lavatory which can be readily installed and which will be sanitary in use.

5 The invention has been developed more particularly in connection with the production of lavatories made of clay, and in the trade known as china or vitreous china, of the one piece type in which the basin, slab and 10 overflow are incorporated in a unitary structure, and for the purpose of illustrating the principles of the invention such an embodiment will be more particularly described, reference being had to the accompanying 15 drawings forming a part hereof and in which—

Figure 1 is a central sectional view of a one piece china lavatory embodying the invention.

20 Figure 2 is a detail view taken on the line 2—2 of Figure 1, and

Figure 3 is a central sectional view of a lavatory in which the integral nozzle inlet is omitted.

25 The lavatory shown in Fig. 1 for the purposes of illustration comprises in one integral structure a basin 5, a slab 6 having a supply nozzle 7 associated therewith, and an overflow passage 8 connected to the basin by 30 an overflow outlet 9 together with a trap 10 below and behind the basin. The overflow outlet 9 is practically concealed beneath the nozzle 7 but easily accessible for cleaning. The inlet leg of the trap is directly in line 35 with and accessible from the overflow passage 8 to facilitate sanitary cleaning thereof. The outlet leg of the trap opens to the rear and is arranged to be suitably connected to a waste pipe 12 in the wall behind the basin. The 40 bottom of the basin is formed with the usual outlet 13, which is connected with the trap 10 and the vertical overflow passage 8 by a horizontal passage 14. The lower wall 15 of this passage is horizontal and parallel to the bottom of the basin and is provided with an aperture 16 in alinement with the outlet 13 to receive a valve fitting 17 carrying a pop up valve 18 which controls the outlet 13. This fitting comprises a cap 18 which, with the 45 washer 19, closes the aperture 16. The valve member 18 comprises a four-wing stem suitably apertured to receive the lower end of the valve operating rod 20 to be lifted thereby.

55 Preferably provision is made for adjustment of the effective length of the valve stem for which purpose is shown the screw threaded connection 21 between the valve head and the stem. The operating means for lifting the valve is effectively concealed 60 within the structure. As shown a valve operating pull rod 20 concealed in the overflow passage 8 is operatively mounted in the opening 22 in the slab and terminates in a convenient knob 23. The fitting by which the rod is 65 mounted within the slab opening may be of any suitable character. In the arrangement shown for the purpose of illustration, a sleeve 25 is secured in its opening by a nut 26 with a suitable yieldable washer 27 therebeneath. The sleeve carries two oppositely disposed lugs 28, one extending forwardly and one rearwardly which bear against the underside of the slab. The opening 22 in the slab is enlarged laterally to facilitate assembly of the fitting. When the lugs 28 are turned through 75 ninety degrees from the position shown in Fig. 2, the sleeve may be inserted through the opening.

If desired the nut 26 and upper end of the 80 sleeve 25 may be concealed behind an escutcheon 30 which is held in position by a suitable nut 31 carried by the upper end of the sleeve 25. The rod 20 which is shown as of adjustable length, the two parts being 85 suitably threaded together, may be held in adjusted position by means of a suitable friction spring 33 within the sleeve 25.

The valve operating rod 20 with its 90 mountings and the valve fitting 17 can be completely removed without interfering with the plumbing connections, and, when these parts are removed, such access may be had to the several waste water passages, including the inlet leg of the trap, as to permit 95 thorough cleaning and the maintenance of sanitary conditions.

The lavatory shown in Fig. 3 is generally 100 similar to that shown in Fig. 1 and comprises an integral basin 35 and slab 36. The overflow passage 38 back of the basin is connected by an overflow outlet 39. Beneath the overflow passage and below and behind the basin is a trap 40, the inlet leg of which is directly beneath and accessible from the overflow passage 38 as in the structure first described. The outlet leg of the trap leads rearwardly and is arranged for connection to the

permanent plumbing as indicated at 42 in the wall behind the basin. The usual outlet 33 from the basin is connected with the trap 40 and with the overflow passage 38 by a horizontal passage 44, the lower wall of which is parallel to the bottom of the basin and provided with an aperture 46 alined with the outlet 43 to receive and be closed by the valve fitting 47 carrying a pop up valve 48. The valve operating pull rod 50 is suitably mounted in the slab and extends downwardly through the overflow passage 38 to operatively engage the waste valve.

In this structure the mounting of the valve pull rod lies relatively close to the rear wall of the basin since space is economized by the absence of the integral nozzle shown in the structure of Fig. 1. In this structure, as in the structure shown in Fig. 1, the inlet leg of the trap is substantially in alinement with the opening through the slab and with the overflow passage to facilitate cleaning to maintain sanitary conditions.

The foregoing particular description is illustrative merely and is not intended as defining the limits of the invention.

I claim:

1. A lavatory comprising a slab, a basin, an overflow passage behind said basin and connected therewith, said overflow passage extending beneath the basin and having a bottom wall parallel with the bottom of the basin, an opening through the slab above said overflow passage, an outlet in the bottom of

said basin communicating with said overflow passage, an opening in said bottom wall of the overflow passage below and in alinement with the basin outlet to receive with said basin outlet a valve for controlling said outlet, and a trap positioned rearwardly of said outlet and having its inlet leg in alinement with said overflow passage and with the opening through the slab, all in one integral structure.

2. A lavatory comprising a slab, a basin, an overflow passage behind said basin and connected therewith, said overflow passage extending beneath the basin and having a bottom wall parallel with the bottom of the basin, an opening through the slab above said overflow passage, an outlet in the bottom of said basin communicating with said overflow passage, an opening in said bottom wall of the overflow passage below and in alinement with the basin outlet and a trap positioned rearwardly of said outlet and having its inlet leg in alinement with said overflow passage and with the opening through the slab and below the level of said opening, all in one integral structure together with a valve controlling the basin outlet comprising a casing member fitting said basin outlet and said opening in the bottom wall of the overflow passage and an operating member for said valve mounted in the opening through the slab and extending through the overflow passage.

WINFIELD E. HINSDALE.
